UNITED STATES PATENT OFFICE.

CHARLES B. SIPPEL, OF CHICAGO, ILLINOIS, ASSIGNOR TO PYRATONE PRODUCTS CORPORATION, OF CHICAGO, ILLINOIS, A CORPORATION OF ILLINOIS.

SHAFT FOR GOLF CLUBS AND THE LIKE.

Application filed March 8, 1928. Serial No. 260,005.

In United States Letters Patent 1,600,389 and 1,600,390, issued September 21, 1926, there is described and claimed an improved shaft for golf clubs and the like in which there is provided a tubular non-metallic covering or casing sleeved and secured upon the core of the shaft. In the former patent the casing is wedged upon the core and in the latter it is shrunk thereupon, thereby rendering it possible in the manufacture thereof to employ low grade material in the formation of the core, the casing being also adapted for use as a covering for hollow metallic cores, the casing or covering not only strengthening and reinforcing the core, but the required flexibility of the shaft will not be interfered with, while at the same time the shaft will be of the desired or required weight and rigidity.

In the manufacture of golf club shafts it is sometimes desired to ornament the same by providing different colors, but with a continuous casing which extends for the length of the shaft between the head and grip of the club it is difficult to produce different clearly designed zones of different colors.

It is one of the objects of the present invention to provide an improved casing or covering of this character which will be of sectional construction whereby a plurality of sections of different colors may be assembled upon a shaft and secured together, the sections being assembled upon the core or before they are placed thereon.

The completed casing or covering is secured to the core in any suitable manner preferably either by shrinking or wedging the same upon the core, sections of different colors being suitably arranged and secured together in any suitable manner, and if desired in a manner so as to resemble a bamboo shaft having joints or protuberances at predetermined intervals throughout the length of the shaft.

To the attainment of these ends and the accomplishment of other new and useful objects as will appear, the invention consists in the features of novelty in substantially the construction, combination and arrangement of the several parts hereinafter more fully described and claimed and shown in the accompanying drawing illustrating this invention, and in which

Figure 1 is an elevation of a golf club shaft constructed in accordance with the principles of this invention.

Figure 2 is an enlarged detail vertical sectional view of a portion of the shaft taken through the casing with the core in elevation and showing one method of connecting the proximate ends of adjacent casing sections.

Figure 3 is a view similar to Figure 2, showing another means of fastening the proximate ends of adjacent sections.

Figure 4 is a view similar to Figure 3, showing another manner of fastening the proximate ends of adjacent casing sections.

Figure 5 is a view similar to Figure 2, showing still another means of securing the proximate ends of adjacent casing sections.

Figure 6 is a detail sectional view taken on line 6—6, Figure 5.

Referring more particularly to the drawing the numeral 10 designates a core formed of any suitable material, here shown as being of a tubular construction and tapered, but it is to be understood that the core may be constructed of any suitable material, may be solid and may be of uniform diameter throughout its length.

Secured about the core 10 is a casing constructed of any suitable non-metallic hard and flexible material, preferably pyroxylin. These sections may be of any desired length and when the core itself is tapered the respective sections of the casing are tapered and the sections progressively taper so that when they are arranged end to end the diameter of the inside of the casing thus formed will be only slightly larger than the external diameter of the core. When the casing thus formed is applied to the outside of the core to strengthen, reinforce and protect the same, it may be secured to the core by either a wedging action or the casing may be shrunk about the core.

In the form of the invention shown in Figures 1 and 2, one end 12 of each of the casing sections 11 is driven into the proximate adjacent end 13 of the next adjacent section so as to secure the sections together and the portion 13 of the respective casing sections will form protuberances or formations designed by the reference numeral 14 in Figure 1, to simulate the joints or protuberances of bamboo, causing the shaft, when finished, to resemble a bamboo shaft.

In the form of the invention shown in Figure 3, one end 15 of each of the casing

sections is shaped so as to receive the proximate end 16 of the next adjacent section in such a manner that the outer peripheries of each of the sections will coincide to present a smooth and unobstructed surface.

In the form of the invention shown in Figure 4, the casing sections 11 are arranged end to end and if desired a joint 17 of any suitable cement may be provided between the 10 adjacent ends of the sections for securing them together, and when this form of the invention is employed and if desired, a coating 18 may be provided around the outer faces of the casing sections.

15 In Figure 5 the proximate ends of the adjacent casing sections 11 are secured together by threading one of the sections into the other, as at 19.

20 In all of the forms of the invention the casing thus formed of sections will tightly fit upon the core.

With this improvement it will be manifest that the casing sections may be manufactured in any desired colors and any combination of 25 colors may be produced by correspondingly assembling the sections end to end, with the result that a very ornamental shaft will be produced.

20 The sections may be secured together and assembled directly upon the core of the shaft or they may be all assembled or connected together before the core is telescoped thereinto.

35 While the preferred forms of the invention have been herein shown and described, it is to be understood that various changes may be made in the details of construction and in the combination and arrangement of the several parts, within the scope of the claims, 40 without departing from the spirit of this invention.

What is claimed as new is:—

1. A flexible golf club shaft embodying a core, and a separate tubular protecting and 45 reinforcing casing of non-metallic hard and flexible material telescoped over the core, said casing being formed of a plurality of separate tubular sections arranged end to end, the proximate ends of adjacent sections being secured together, said casing and core having contact throughout the length of the casing and being independent of each other.

55 2. A flexible golf club shaft embodying a tapered core, and a separate tapered tubular 50 casing of non-metallic hard and flexible material telescoped over and closely fitting the core, said casing being formed of a plurality of separate tubular sections arranged end to end, the proximate ends of adjacent sections 60 being secured together.

65 3. A shaft for golf clubs and the like embodying a flexible core and a flexible tubular casing of non-metallic hard and flexible material telescoped upon and shrunk about the core, said casing being formed of a plurality

of separate sections arranged end to end, the proximate ends of adjacent sections being secured together.

4. A shaft for golf clubs and the like embodying a flexible core and a flexible tubular 70 casing of pyroxyline telescoped upon and shrunk about the core, said casing being formed of a plurality of separate sections arranged end to end, the proximate ends of adjacent sections being secured together. 75

5. As an article of manufacture an extended tubular casing of non-metallic hard and flexible material of a diameter to closely fit upon a golf club shaft to have contact with the shaft throughout the length of the casing, 80 said casing being formed of a plurality of sections arranged end to end, the proximate ends of adjacent sections being secured together.

6. As an article of manufacture an extended tapered tubular casing of non-metallic hard and flexible material of a diameter to closely fit upon a golf club shaft to have contact with the shaft throughout the length of the casing, 85 said casing being formed of a plurality of continuously tapered sections arranged end to end, the proximate ends of adjacent sections being secured together. 90

7. As an article of manufacture an extended tubular casing of pyroxyline of a diameter 95 to closely fit upon a golf club shaft to have contact with the shaft throughout the length of the casing, said casing being formed of a plurality of sections arranged end to end, the proximate ends of adjacent sections being secured together. 100

8. As an article of manufacture an extended tapered tubular casing of pyroxyline of a diameter to closely fit upon a golf club shaft to have contact with the shaft throughout the length of the casing, 105 said casing being formed of a plurality of continuously tapered sections arranged end to end, the proximate ends of adjacent sections being secured together. 110

9. A flexible shaft embodying a core, and a separate tubular protecting and reinforcing casing of non-metallic hard and flexible material telescoped over the core, said casing being formed of a plurality of separate tubular sections arranged end to end, the proximate ends 115 of adjacent sections being secured together, said casing and core having contact throughout the length of the casing and being independent of each other.

10. A flexible shaft embodying a tapered 120 core, and a separate tapered tubular casing of non-metallic hard and flexible material telescoped over and closely fitting the core, said casing being formed of a plurality of separate tubular sections arranged end to end, the proximate ends of adjacent sections being secured together. 125

11. A golf club shaft embodying a core, a separate tubular protecting casing of non-metallic, hard and flexible material encom- 130

passing the core, said casing being formed of a plurality of separate sections arranged end to end, the proximate ends of adjacent sections being disposed in close proximity to each other.

12. A golf club shaft embodying a core, a separate tubular protecting casing of non-metallic, hard and flexible material encompassing and closely fitting the core, said casing being formed of a plurality of separate sections arranged end to end, the proximate ends of adjacent sections being disposed in close proximity to each other.

13. A golf club shaft embodying a core, a separate tubular protecting casing of non-metallic, hard and flexible material encompassing the core, said casing being formed of

a plurality of separate and tapered sections arranged end to end, the proximate ends of adjacent sections being disposed in close proximity to each other.

14. A golf club shaft embodying a core, a separate tubular protecting casing of non-metallic, hard and flexible material encompassing and closely fitting the core, said casing being formed of a plurality of separate and tapered sections arranged end to end, the proximate ends of adjacent sections being disposed in close proximity to each other.

In testimony whereof I have signed my name to this specification, on this 4th day of November, A. D., 1927.

CHARLES B. SIPPEL.
